SIGNAL LAMP

Filed Sept. 13, 1927

UNITED STATES PATENT OFFICE

PIERRE PAUL BASTERREIX, OF BUTTE, MONTANA

SIGNAL LAMP

Application filed September 13, 1927. Serial No. 219,279.

This invention relates to a signal lamp, and particularly to a construction having direction signals at its opposite faces and a stop signal and tail light associated with the direction signal at one face.

In the construction of signals of this character such as shown in my application filed November 30, 1925, Serial No. 72,197, it is desirable to provide for both a stop and tail light in cooperation with the opposite signal designations illuminated by a signal lamp. Such construction provides for greater utility of the signal lamp by incorporating an additional element therein and still utilizing the partitions as reflecting surfaces cooperating with a reflecting surface upon the inner face of one of the signal plates disposed in alignment with the lamp for signal illumination.

I have therefore provided a construction of casing having at its opposite faces signal designations and a substantially horizontal partition extending between such faces with an inner reflecting surface. Beneath this horizontal partition a vertical partition is disposed which provides a chamber for a tail light while above the horizontal partition I form a vertical partition extending downward intermediate the opposite faces of the casing and rearwardly to the back face thereof. Both the inner and outer faces of this vertical partition are formed with reflecting surfaces one of which cooperates with the lamp for direction signals and the other with a lamp in the chamber formed above the vertical partition and adapted to receive a lamp for the stop designation.

This construction is adapted to cooperate with a front closure plate having a signal designation at its upper portion and a reflecting surface below the same, and also with a rear closure plate having a plurality of signal designations and a lower cut away portion cooperating with the tail lamp.

Other and further objects and advantages of the invention will be hereinafter set forth and the novel features thereof defined by the appended claim.

In the accompanying drawing:

Figure 1 is a front elevation;

Figure 2 is a rear elevation;

Figure 3 is a vertical longitudinal section; and

Figure 4 is a detail on line 4—4 of Figure 3.

The numeral 10 designates a lamp casing which may be of any desired size or configuration and provided with a suitable bracket 11 by which it may be mounted upon a fender or other part of an automobile so as to be visible from the front and rear thereof. The opposite open ends of this casing are provided with transparent closures 12 of any desired color, for instance red, and at the rear of these closures, signal plates 13 and 14 are disposed. These parts are clamped and retained in relation to the casing by means of the usual construction of rim 15 having bayonet joint connections with a screw or stud 16 mounted in the casing.

The front plate 13 is formed at its upper portion with a signal designation 17, in the present instance referring to direction of turn of the vehicle, and the lower portion of this plate has a reflecting surface 18. The rear plate 14 is formed with an upper signal designation 19 and a lower designation 20, the latter referring to direction and cooperating with the designation 17 of the front plate. The lower portion of the rear plate is cut away as at 21 to cooperate with a suitable lamp such as a tail light 22.

Connected to the body of the casing and extending from the front to the rear signal plates I provide a substantially horizontal partition 23 having an inner reflecting surface 24 and an opposite reflecting surface 25 at one end thereof. Beneath this partition a vertical wall 26 is provided which divides the space into a rear chamber 27 for the tail light and a front chamber 28 for the socket for said light and the electrical connections thereto. At one side of the horizontal partition 23 a lateral bracket 31 is secured to the casing and carries the lamp 32 for illuminating the space above the partition.

Intermediate the opposite signal faces of the lamp a vertical partition 33 is provided which extends downwardly and rearwardly to the rear signal plate as at 34 having an inner reflecting face 35 and an outer reflect-

ing face 36, the latter cooperating with the lamp 32 for the chamber formed between this partition and the horizontal partition. The vertical partition 33 forms a stop light chamber 37 and a support for the socket of the lamp 38 therein, while the electrical connections 39 for this lamp are disposed above the signal designations 17 of the front plate.

The lower portion of the casing is provided with an opening 40 communicating with the tail light chamber 27 by which the usual license plate will be illuminated. The inner face of the casing 10 where it forms part of the several lamp chambers is provided 15 with a reflecting surface.

It will be seen that the construction presented is of a simple character adapted to secure very efficient results and secure the maximum illumination for the tail and stop 20 light designations without interfering with the efficient use of the opposite signal designations. The lamp for illuminating the latter is mounted at one side of the casing so that its socket does not interfere with the proper 25 passage of light to the signal plates and this lamp is disposed out of direct alignment with the direction signals so that its rays are reflected by the inner walls of the partitions to secure a proper illumination of the signals 30 without such an intense ray as would be objectionable or blinding.

In the operation of the signal the circuit to the direction lamp is manually controlled while a separate circuit is maintained for the 35 tail light in order that it may be continuously illuminated when in use. The stop lamp circuit may be either manually operated or automatically connected to the brake mechanism, as is common in the art.

The specific construction of the several 40 parts has been shown and described but the invention is not confined thereto as changes and alterations may be made without departing from the spirit thereof as defined by the 45 following claim.

Having thus described my invention, what I claim as new and desire to secure by Letters Patent of the United States, is:—

A signal lamp including a casing having 50 opposite face plates, one of said plates bearing a plurality of signal designations and the other of said plates at least one signal designation; a substantially horizontal partition at the lower portion of the said casing 55 having an upper reflecting surface and providing with the casing a lamp chamber beneath said partition, and another partition having a vertical portion extending downwardly from the upper portion of said casing 60 intermediate the opposite plates and thence laterally above said horizontal partition to a point intermediate the signal designations upon one plate to provide at its vertical portion a support for a lamp and at its lateral 65 portion upper and lower chambers cooperat-

ing with corresponding signal designations, and a lamp in said lower chamber for cooperating with the same signal designations on said opposite plates.

In testimony whereof I affix my signature. 70
PIERRE PAUL BASTERREIX.
